UNITED STATES PATENT OFFICE

127,912

DESIGN FOR A BOTTLE

Alfred L. Ogle, Lincoln, Nebr.

Application May 6, 1941, Serial No. 100,807

Term of patent 3½ years

To all whom it may concern:

Be it known that Alfred L. Ogle, a citizen of the United States, residing at Lincoln, in the county of Lancaster and State of Nebraska, has invented a new, original, and ornamental Design for a Bottle, of which the following is a specification, reference being had to the accompanying drawing, forming part thereof, wherein—

I claim:

The ornamental design for a bottle, as shown.

ALFRED L. OGLE.
